UNITED STATES PATENT OFFICE.

AARON D. SHREVE, OF KEARNEY, NEBRASKA.

INSECTICIDE AND DISINFECTANT.

1,399,585.

Specification of Letters Patent.

Patented Dec. 6, 1921.

No Drawing.

Application filed August 5, 1918. Serial No. 248,830.

To all whom it may concern:

Be it known that I, AARON D. SHREVE, a citizen of the United States, residing at Kearney, in the county of Buffalo and State 5 of Nebraska, have invented certain new and useful Improvements in Insecticides and Disinfectants, of which the following is a specification.

This invention is a compound for use as a 10 disinfectant and insecticide to rid poultry and animals of parasites and promote the cleanliness and general health of the stock.

In carrying out my invention, I first make 15 a liquid insecticide by mixing ten gallons each of crude tar oil and the liquid refuse or by-product known as high pressure carbon, which is deposited during the conversion of oil into gas.

The insecticide may be given disinfectant 20 properties by adding a minor proportion of other ingredients. For instance, as much as five gallons of crude carbolic acid may be mixed with the twenty gallons above, and about five pounds each of sodium chlorid and sodium oxid. All ingredients are 25 now thoroughly admixed by agitating or stirring.

The compound may be applied to the 30 fowls or animals by spraying or washing them with it, or it may be left in receptacles in the stable, barn, pen, or poultry house; in fact stalls, perches, etc., may be washed

or sprayed with the compound whose odor is so objectionable that stock and fowls will not eat of it to their injury.

This compound is not expensive and is 35 highly efficient for the purposes for which it is intended. The crude tar oil forms a body or vehicle for holding the other ingredients, and the carbon throws off fumes which 40 are deadly to all insects which tend to bury themselves in the hair or feathers and feed upon the flesh of the stock. The carbolic acid, chlorid of sodium and oxid of sodium aid to some extent in destroying the parasites, and have the additional function of 45 disinfecting the body and the premises in which the stock may be housed so that the general cleanliness and sanitary conditions under which the stock is maintained will be 50 increased and the general health of the fowls or animals promoted.

Having thus described my invention, what is claimed as new is:

A composition for the purpose set forth 55 consisting of a mixture of the following ingredients in about the proportions stated: crude tar oil, ten gallons, carbon produced during the conversion of oil into gas and known as high pressure carbon, ten gallons, 60 carbolic acid, five gallons, sodium chlorid, five pounds, and sodium oxid, five pounds.

In testimony whereof I affix my signature.

AARON D. SHREVE. [L.S.]
